UNITED STATES PATENT OFFICE.

CHRISTIAN SEIDEL, OF NEW YORK, N. Y., ASSIGNOR TO J. HENRY PETERS COMPANY, OF SAME PLACE.

DESIGN FOR A SKIRT-BINDING.

SPECIFICATION forming part of Design No. 34,296, dated March 26, 1901.

Application filed February 26, 1901. Serial No. 48,997. Term of patent 7 years.

To all whom it may concern:

Be it known that I, CHRISTIAN SEIDEL, a citizen of the United States, and a resident of the borough of Manhattan, in the city and State of New York, have invented a new and original Design for a Skirt-Binding, of which the following is a specification.

The essential features of my design consist in a skirt-binding comprising a head presenting a column-like effect of wave, a brush pendent from one edge of the head, a horizontal line of cord-like effect spaced a short distance from the brush, the column-like effect below the cord-line presenting a series of short parallel columns and above the cord-line the columns presenting a zigzag effect, with the binding - threads prominent at the points where the zigzag columns approach nearest one another.

The accompanying drawing presents a piece of the braid in side elevation.

The head is denoted as a whole by *a*, the brush pendent from one edge thereof by *b*, the series of short parallel columns in proximity to the brush by *c*, the zigzag columns 25 above the cord-line *d* being denoted by *e*, and the binding - threads prominent at points where the zigzag columns approach nearest each other by *f*.

What I claim is—

The design for a skirt-binding, substantially as shown and described.

In testimony that I claim the foregoing as my invention I have signed my name, in presence of two witnesses, this 20th day of February, 1901.

CHRISTIAN SEIDEL.
